Suncast Catalog, p. 3, hose reels Aug. 15, 1995.

Primary Examiner—Susan B Hattan(74) *Attorney, Agent, or Firm*—Fraser Clemens Martin & Miller LLC; William J. Clemens(57) **CLAIM**

The ornamental design for a cord reel, as shown.

DESCRIPTION

FIG. 1 is a front perspective view of a cord reel of the present invention;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.
